(57) **CLAIM**

The ornamental design for a handbag as shown and described.

DESCRIPTION

FIG. 1 is a front top right perspective view of a handbag, in accordance with an embodiment, in a first configuration; FIG. 2 is a front top perspective view of the handbag of FIG. 1;

FIG. 3 is a rear top perspective view of the handbag of FIG. 1;

FIG. 4 is a top front perspective view of the handbag of FIG. 1;

FIG. 5 is a bottom view of the handbag of FIG. 1;

FIG. 6 is a right side view of the handbag of FIG. 1;

FIG. 7 is a left side view of the handbag of FIG. 1;

FIG. 8 is a front top right perspective view of the handbag of FIG. 1 in a second configuration;

FIG. 9 is a front top perspective view of the handbag of FIG. 8;

FIG. 10 is a top front perspective view of the handbag of FIG. 8;

FIG. 11 is a right side view of the handbag of FIG. 8;

FIG. 12 is a left side view of the handbag of FIG. 8;

FIG. 13 is a rear top left perspective view of the handbag of FIG. 8; and,

FIG. 14 is a front top left perspective view of the handbag of FIG. 1 in a third configuration.

The ornamental design which is claimed is shown in solid lines in the drawings. The broken lines formed by dashes of equal lengths in the drawings are for illustrative purposes only and form no part of the claimed design. The broken lines formed by dashes of unequal lengths in the drawings illustrate boundaries between claimed subject matter and non-claimed subject matter.

1 Claim, 14 Drawing Sheets
